UNITED STATES PATENT OFFICE.

ALBERT BETHINCOURT, OF NEW YORK, N. Y.

COMBINED COMB AND BRUSH.

1,390,332.

Specification of Letters Patent. Patented Sept. 13, 1921.

Application filed April 30, 1921. Serial No. 465,683.

To all whom it may concern:

Be it known that I, ALBERT BETHINCOURT, a citizen of the United States, residing at New York, in the county of the Bronx and 5 State of New York, have invented certain new and useful Improvements in Combined Combs and Brushes, of which the following is a specification.

This invention relates to improvements in 10 toilet kits and has for its principal object to provide a combination including a comb, brush and mirror so assembled when in closed position as to provide a compact package which may be readily placed in the 15 pocket for transportation.

Another object of the invention resides in 20 the provision of a rust proof mirror formed of an unbreakable material such as aluminum, steel or the like, which also is designed to stiffen the case back and enable the case when turned inside out to stand in an up-right position.

With these and other objects in view the 25 invention consists in the novel construction, combination and arrangement of parts which will be fully set forth in the following specification, claimed and illustrated in the accompanying drawing, in which,

Figure 1 is a back view of the combined 30 comb and brush, showing portions broken away to more clearly illustrate the details of construction,

Fig. 2 is an edge view of Fig. 1, and

Fig. 3 is a perspective view of the case and 35 mirror.

Referring to the drawing in detail the numeral 10 designates in its entirety the brush comprising a back 11 in which bristles 12 are secured in any preferred manner. The 40 back 11 is provided along one of its marginal edges with a longitudinal groove 13 provided adjacent one end with a pivot 14 upon which the comb 15 is pivotally mounted.

In order to provide a suitable carrier for 45 the device a cover designated by the numeral 16 comprising a body member 17 is provided at opposite longitudinal edges with flaps 18 and 19. The end edges of the body

are provided with the end flaps 20 and 21, one of which is provided with a ring 22 by 50 means of which the device may be suspended. Secured as at 23 adjacent the corners of the body 17 is a mirror 24 formed of a suitable rust-proof non-breakable material such as aluminum, steel or the like. As shown in 55 Fig. 3 the flaps 18, 19, 20 and 21 may be stiffened as at 25 so that when the device is folded a substantially boxlike structure will be provided for the reception of the brush 10. The flaps 18 and 19 are provided near 60 their outer edges with co-operating members of suitable fastening means such as snap fasteners and it will thus be seen that when the brush is placed on the plate 24 the flaps 20 and 21 may be folded over opposite ends 65 and secured in place by the overlapping portions of flaps 18 and 19 and secured by the fastening means.

Obviously when it is desired to stand the 70 device in an upright position to use the mirror the flaps are bent into the opposite position and will afford a stand.

While in the foregoing there has been shown and described the preferred embodiment of this invention it is to be understood 75 that minor changes in the details of construction, combination and arrangement of parts may be made without departing from the spirit and scope of the invention as claimed.

What is claimed is:

1. A cover for a toilet kit comprising, a body, flaps along the marginal edges of the body, a mirror secured to the inner side of the body and means for holding the flaps in 85 position to support the mirror in upright position.

2. A cover for a toilet kit comprising, a body, flaps along the marginal edges of the body, a mirror secured to the inner side of 90 said body, stiffening means in the flaps for holding the body and mirror in an upright position and means for securing the flaps in closed and open position.

In witness whereof I affix my signature.
ALBERT BETHINCOURT.
